UNITED STATES PATENT OFFICE

WALTER S. MAYER, OF PHILADELPHIA, PENNSYLVANIA

BUS SUPPORT

Application filed August 29, 1925. Serial No. 53,252.

My invention is an improved support for carrying and insulating a bus conductor and comprises an insulating body, preferably of vitreous material, and coupling for connecting base and conductor clamps with the insulator without decreasing the effective flash-over value thereof. By my improvements, stresses are transmitted directly from a coupling to an integral part of the insulator 10 forming a bearing surface normal to or intersecting the lines of force, and the need of cement or adhesives for securing the couplings to the insulator is obviated.

In accordance with my invention, an insulator, preferably moulded from porcelain by the wet process and having a height equal to the desired flash-over value, has set therein 15 couplings so positioned that the open path between them is equal to or longer than the flash-over distance between the insulator ends. One or both of the couplings has a detachable head seated in a groove or channel extending transversely to the height of the insulator, and a shank or stem, connected with 20 such head, extends through a bore or channel leading from the groove to the end of the insulator for the engagement thereto of a base or conductor clamp. When the insulator is formed of porcelain or other vitrifiable 25 material, the coupling channels are preferably formed before baking and the coupling members inserted after baking and cooling of the insulator.

The characteristic features and advantages 30 of my improvements will further appear from the following description and the accompanying drawings illustrating embodiments of my invention.

In the drawings, Fig. 1 is a longitudinal 35 sectional view of a form of my improved support taken on the line 1-1 of Fig. 2; Fig. 2 is a side elevation of the support shown in Fig. 1 without the clamps; Fig. 3 is a top plan view of the device shown in Figs. 1 and 40 2; Fig. 4 is a fragmentary elevation of the device opposite the side shown in Fig. 2; Fig. 45 5 is a longitudinal sectional view of a modified form of device embodying my invention; Fig. 6 is a longitudinal sectional view of a 50 further form of device embodying my in-

vention; and Fig. 7 is a longitudinal sectional view of a further form of device embodying my invention.

As illustrated in Figs. 1 to 4, inclusive, a vitreous insulator 1, having its periphery 2 55 corrugated to increase the creepage surface, has a flash-over height measured by the distance between its end surfaces 3 and 4.

The insulator is preferably formed of wet process porcelain to afford maximum resistance to electric and atmospheric conditions but may be formed of other suitable dielectric substances.

Radial slots 5, 5', transverse to the height of the insulator, extend inwardly from opposite sides of its periphery toward the center thereof. Axial bores 6, 6' extend from the respective ends 3 and 4 toward one another and respectively intersect the slots 5, 5'. The apertures 5, 5', 6, 6' are preferably cut in the insulator after moulding and before baking when the insulators are made of wet process porcelain, but may be formed during die casting when a fluid dielectric is used for making the insulator. 70

The insulators have suitable base and bus-conductor clamps 7, 7' secured thereto by couplings comprising nuts or heads 8 held against turning by the engagement of their flat sides with the side walls of the slot and containing threaded sockets for the reception of threaded shanks or stems of bolts 9 having heads engaging the clamps. A cushioning washer 10 may be inserted between the insulator and one or both clamps. 75

The heads 8 are dropped into the slots 5, 5' and the bolt shanks 9 are passed through the clamps and bores 6, 6' and screwed into the sockets of the heads. After the assembly of the parts, the insulator apertures may be filled with a sealing wax or other non-conducting filler to exclude moisture and dirt. 80

It will be observed that the stresses are transmitted directly to integral portions of the insulator through bearing surfaces of the grooves 5, 5' intersecting the lines of force; the couplings are accurately positioned without the use of jigs and firmly secured without the use of cement; and the 100

flash-over value of the insulator is not diminished because the path from one head 8, through the groove 5, around half the circumference of the insulator and through the 5 groove 5' to the other head 8 is considerably longer than the distance between the ends 3 and 4.

In the form of the device shown in Fig. 5, the grooves 5a and 5a' extend entirely 10 through the insulator at right angles to one another and a lock washer 11 is inserted between one of the heads 8 and the porcelain wall transverse thereto. As the distance from one nut 8 to the other through the 15 grooves 5a and 5a' and part way round the circumference of the insulator is greater than the height of the insulator, there is no diminution of flash-over value.

Fig. 6 illustrates the provision of a plurality of couplings at one end of the insulator. In this form of the device, the groove 20 5a is separated by a barrier 1a into several sections each containing a head 8 and communicating with a bore 6a leading to the end 25 3 for the passage of a stem 9. The opposite end of the insulator contains channels 5a' and 6' with the coupling members 8 and 9 therein similar to the showing in Fig. 5. The bores 6a and 6' may be extended slightly 30 beyond the grooves 5a, 5a' to form recesses 12 permitting the stems of the bolts 9 to be screwed slightly past the inner surfaces of the heads 8. In this construction also the distance from either head 8 in the 35 channel 5a to the head 8 in the channel 5a' is equal to or greater than the flash-over height between the ends 3 and 4.

In the form shown in Fig. 7, one end of the insulator 1 contains channels 5', 6' containing coupling members 8 and 9, similar to 40 the showing of Fig. 1, while the other end of the insulator contains a recess 13 in which the coupling thimble 14 is secured by cement 15. The thimble contains a threaded hole 45 16 for the reception of a clamp bolt. The groove 5' is shown filled with sealing wax. As in the other figures, the electrical path 50 between the coupling member 15 and the coupling 8, 9 is equal to or greater than the height of the insulator, hence there is no sacrifice of flash-over value.

It will be understood that the details or modifications indicated by the numerals 10, 11, 12, 13, 14, 15 and 16 are applicable to the 55 several forms of the device. In each form of the device, the distance which the couplings penetrate axially within the insulator is compensated for by the distance between the couplings and the periphery of the insulator, so that the flash-over distance between 60 couplings is never less than the flash-over value determined by the height of the insulator, or the distance between its ends.

Having described my invention, I claim:

65 1. A bus conductor support comprising an

insulator having separate channels extending from opposite sides into and slightly beyond the center of said insulator, channels communicating with said channels first named and adapted to accommodate coupling members which are secured by nuts located in said first named channels.

2. A bus conductor support comprising an insulator body having a channel extending radially from the outer periphery thereof toward the interior and a channel forming an opening in an end of said body and communicating with the channel first named, and coupling means comprising a detachable head seated in said first channel and a shank disposed in said second channel, the flash over distance between said head and the plane of the end of said body opposite said first named end being no less than the flash over distance between the planes of the ends of said body.

In testimony whereof I have hereunto set my name this 25th day of August, 1925.
